D. FOERSTER, OF ZANESVILLE, OHIO.

Design No. 3,260, dated November 17, 1868.

DESIGN FOR A TRADE-MARK

The Schedule referred to in these Letters Patent and making part of the same.

To all whom it may concern:

Be it known that I, D. FOERSTER, of Zanesville, in the county of Muskingum, and State of Ohio, have invented a new and original Design for a Trade-Mark for Crackers; and I do hereby declare that the following is a full, clear, and exact description thereof, which will enable others skilled in the art to make and use the same, reference being had to the accompanying drawing, forming part of this specification.

This invention relates to a new and original design for a trade-mark for lemon-crackers; and it consists in a representation of a branch of a lemon-tree, having leaves and a lemon attached, with the word "Lemon" marked on the fruit, the word "Foerster's" marked over the design, and the word "Crackers" underneath it.

The accompanying drawing represents my design.

A represents a branch of a lemon-tree, B, the leaves, and C, a lemon attached; the word "Lemon" being painted, stencilled, or otherwise marked upon the fruit, the word "Foerster's" marked above the design, and the word "Crackers" marked underneath it, as plainly shown in the drawing.

Having thus described my invention,

I claim as new, and desire to secure by Letters Patent—

A design for a trade-mark for crackers, substantially as shown and described.

D. FOERSTER.
